UNITED STATES PATENT OFFICE

DAVID H. ZELL, OF BROOKLYN, NEW YORK

DESIGN FOR A COVER FOR VANITY CASES OR ANALOGOUS ARTICLES

Application filed November 15, 1928. Serial No. 28,894. Term of patent 7 years.

To all whom it may concern:

Be it known that I, DAVID H. ZELL, a citizen of the United States, residing at Brooklyn, in the county of Kings and State of New York, have invented a new, original, and ornamental Design for Cover for Vanity Cases or Analogous Articles, of which the following is a specification, reference being had to the accompanying drawing, forming part thereof.

The drawing represents a plan view showing my new design.

The article consists of a thin flexible sheet of leather or other fibrous material capable of use as a cover to one side of which the surface ornamentation is applied.

I claim:

The ornamental design for a cover for vanity cases or analogous articles, as shown and described.

DAVID H. ZELL.
